SLIDABLE FASTENING DEVICE

Filed July 22, 1931

UNITED STATES PATENT OFFICE

JOHN A. H. SIERS, OF JERSEY CITY, NEW JERSEY

SLIDABLE FASTENING DEVICE

REISSUED

Application filed July 22, 1931. Serial No. 552,314.

This invention relates to fastening devices that have been applied to the margins of connecting portions of garments, luggage, etc., which comprise a series of successive interlocking members adapted to be brought together or separated by means of a slidable member which manipulates the interlocking parts in the proper way.

The object of the present invention is to 10 provide a fastener of the type described that is not only simple and inexpensive to manufacture, but also one that may be applied to overlapping portions of fabric, leather, or other materials which may form closures 15 for garments, luggage and other articles, and to arrange the same in such a manner that the overlapping portions of the material to which the fasteners are attached cause the fasteners to become substantially invisible, 20 so that the same are not unsightly and objectionable as a disfiguring feature of the articles to which they are applied.

A further object of my invention is to provide a new form of interlocking members 25 which interlock with great positiveness and are not easily separated except when the operating or slidable member is moved on them in the proper manner.

For a detailed description of one form of 30 my invention which I at present deem preferable, reference may be had to the following specification, and to the accompanying drawings forming a part thereof, in which Fig. 1 is a plan view of my improved interlocking elements and the slidable member which operates thereon.

Fig. 2 is a sectional view similar to the 35 central portion of Fig. 1, and showing the elements of the locking devices in section.

Fig. 3 is a perspective view of the female 40 element of the locking device.

Fig. 4 is a perspective view of the male element thereof.

Fig. 5 is a transverse sectional view taken 45 substantially on the line 5—5 of Fig. 2.

Fig. 6 is a sectional view taken substantially on the line 6—6 of Fig. 2.

Fig. 7 is a plan view showing one-half of 50 the member for closing and opening the interlocking elements.

It will, of course, be appreciated that the figures of the drawings show the elements and members of the fastening device greatly enlarged, so that their details may be easily seen.

Referring to the drawings, the numeral 1 indicates a suitable strip of fabric or similar material, preferably in the form of tape, on which the locking elements 2 and 3 are mounted or fastened. The strips or tapes 1 55 may be applied to flexible material such as fabric, leather, etc., in any suitable manner, but, as indicated in Fig. 5, said tapes are preferably stitched to said fabric or members 4 and 5 which the fastener connects together.

It is, of course, obvious that my improved fastening device need not necessarily be applied to overlapping portions of fabric, etc., as indicated in Fig. 5, but, by suitably designing the parts of the fastener which connect the fabric, the fastening device may be applied to the edges of the fabric as is done in some fastening devices heretofore known in the art.

Referring now particularly to Figs. 3 and 4, it will be seen that the female element of the fastener 3 is shown as being made from a strip of metal which terminates in two prongs or substantially triangular pieces 6 70 and 7. The remainder of the metallic strip consists of two doubled portions 8 and 9, to form projections adapted to engage or clamp on the tape or fabric on which the element is mounted. The central portion of the strip is also doubled upon itself, as indicated at 10, forming a transverse flat head which is provided with a short slot 11. The connecting portions of the female element 3 are preferably slightly separated from each other a distance substantially equal to the width of the slot 11, as indicated at 12. The flanges extending from the doubled portion 10 are adapted to be engaged by the slider for opening and closing the fastener, as indicated in Fig. 5.

In Fig. 4, the male element of the fastener is also made from a strip of metal, the ends of which are provided with the prongs or triangular portions 13 and 14. Said strip is also 100

doubled on itself to form the projections 15 and 16, said projections also being for the purpose of engaging the tape or fabric upon which the element is mounted. Said strip is 5 also doubled upon itself to provide two additional transverse projections or flanges 17 and 18, which correspond to the doubled portion 10 and flanges above referred to, and enable the opening and closing slider to engage 10 the same as indicated in Fig. 5. The central portion of the strip is doubled upon itself to form the head or male member of the fastener 15, which is provided with a reduced portion or neck 20, which is adapted to be contained 15 within the slot 11 in the female member.

The manner in which these members engage each other to form the closure, is clearly illustrated in the lower part of Fig. 2. It will be seen from that figure that the female 20 elements 3 are attached to the tape 1 successively and in close proximity with each other, the attachment being made by inserting the prongs 6 and 7 through the fabric and then bending the same transversely so that they 25 lie flat upon the underside of said tape or fabric, as is well known in the art. This arrangement of said members causes the successive slots 11 to be in substantial alignment along the length of the tape, and the portion 30 of the head 10 which is continuous beyond the slot, forms what amount to transverse bars 21, which retain the enlarged heads of the male element 19 in position when inserted therebetween, as clearly indicated in Fig. 2.

Referring now to Fig. 7, it will be seen that the member for interlocking and separating the fastening elements, comprises a member preferably made of sheet metal which consists of two similar corresponding parts 40 which are held together by suitable pins or otherwise, which pins may pass through the holes 22. This member includes a grooved portion 23, the upper end of which branches into the separate grooves 24 and 25, said 45 grooves being formed by the central raised triangular projection 26 through which the holes 22 pass. One-half of this member is also provided with a cylindrical part 27, through which a bar 28 of a handle 29 may 50 pass. This handle obviously may be used to move the slidable fastening member in either direction, to operate the fastening elements.

Referring now to Fig. 2, this movement is accomplished, for instance, for closing or 55 interlocking the fastening elements, by causing the head 19 of the right hand element to pass within the slot 11 of the corresponding left-hand element, and since there is an angle, as indicated at 30, between two successive slotted elements, the heads 19 are permitted to enter between the edge of the cross-bar 21 and the edge of the adjacent cross-bar on the next slotted element. As the 60 operating member moves still further upward, its flanges engage the flanges projecting from

the heads and the adjacent interlocking element moves up to the open end portion of the slot 11, and the cross-bar 21 is caused to enter the recess below the head 19, so that the neck portion 20 of said head cannot leave 70 its corresponding slot 11. This action continues successively as the slidable locking member is pulled upward to cause the elements to interlock. The reverse action takes 75 place to separate said elements when the locking member is pulled downward, or toward the bottom of the sheet of the drawing.

By referring to Fig. 5, it will be noticed 80 that the slots 23 in the slidable locking member lie wholly between the surfaces of the fabric or superposed portions of the flexible material 4 and 5 which are fastened together by the locking elements. The handle 25, the cylindrical loop 27, and the other parts connected with the slidable locking member, are 85 therefore entirely concealed and are only apparent when it is desired to open or close the edges of the fabric or other material to which the fasteners are attached.

Having thus described this form of my invention, I do not wish it to be understood 90 as being limited to the details of form or specific arrangements of parts herein set forth, for various changes may be made in the design of the fastener without departing from 95 the spirit and scope of my invention, as set forth in the appended claims.

What I claim and desire to protect by Letters Patent, is as follows:

1. In a fastening device for flexible material, including a slider and comprising two series of interlocking elements, one series of said elements being provided with enlarged heads and the other series being provided with openings through which said heads may 100 pass when said elements are separated from each other, the improvement which comprises providing said elements with substantially flat portions so positioned as to lie adjacent each other when the opposite elements are in engagement, said flat portions forming transverse flanges which are engaged by said slider to cause the respective elements of said series successively to engage and disengage each other.

2. In a fastening device for flexible material, including a slider and comprising two series of interlocking elements, one series of said elements being provided with enlarged heads and the other series being provided with openings through which said heads may 105 pass when said elements are separated from each other, the improvement which comprises providing said elements with substantially flat portions so positioned as to contact with those in the opposite series when the elements are in engagement, said flat head portions forming transverse flanges which when said elements are positioned adjacent each other 110 form substantially continuous lateral ribs 115

which are engaged by said slider to cause the respective elements of said series successively to engage and disengage each other.

3. A fastening device for flexible material, comprising two series of interlocking elements cut from sheet material, one series of said elements being provided with enlarged heads of doubled material, and the elements of the other series each being provided with 10 a single slot through which one of said heads may pass and within which it is retained, said slots being obstructed respectively by the adjacent cross portions of said elements and allowing the entry and withdrawal of 15 said heads only when adjacent elements are positioned at an angle to one another.

4. A fastening device for flexible material, comprising two series of interlocking elements cut from sheet material, one series 20 of said elements being provided with double layers of said material forming enlarged heads, and the elements of the other series each being provided with a single slot through which one of said heads may pass 25 and within which it is retained, said slots being obstructed respectively by the adjacent straight cross portions of said elements and allowing the entry and withdrawal of said heads only when adjacent elements are positioned at an angle to each other.

5. A fastening device for flexible material, comprising two series of interlocking elements, the elements of each series being provided with lateral projections forming bases 35 therefor, superposed pieces of flexible material to which said bases are attached whereby said elements extend at right angles thereto, and a slideable member lying substantially entirely between said pieces of flexible material and engaging said elements, the movements of which cause said elements to interlock and to separate from each other.

6. A fastening device for flexible material, comprising two series of interlocking elements, one series of said elements being provided with enlarged heads, and the other series being provided with openings through 45 which said heads may pass and within which they are retained, said elements also being provided with transverse flanges forming substantially continuous ribs and with flat bases extending at right angles to said elements, said ribs and said bases forming grooves therebetween, pieces of flexible material on which the bases of said series of 55 elements are respectively mounted so as to extend transversely therefrom and a flanged slideable member adapted to operate in said grooves on said elements and located between said pieces of material and by the movements of which said series of elements are respectively caused to interlock and to 60 separate from each other.

7. A fastening device for flexible material, 65 comprising two series of interlocking ele-

ments, one series of said elements being provided with enlarged heads, and the other series being provided with openings through which said heads may pass and within which they are retained, superposed pieces of flexible material on which said series are respectively mounted so as to extend laterally therefrom, and a slideable member engaging said elements and located substantially entirely between the adjacent surfaces of 70 said pieces of material and by the movement of which said series of elements are respectively caused to interlock and to separate from each other.

8. A fastening device for flexible material, comprising two series of interlocking elements, one series of said elements being provided with enlarged heads and the other series being provided with slots through which 75 said heads may pass and within which they are retained, said slots being obstructed respectively by the adjacent elements and allowing the entry and withdrawal of said heads only when said adjacent elements are positioned at an angle to each other, superposed pieces of flexible material on which 80 said series of elements are respectively mounted so as to extend laterally therefrom, and a slideable member engaging said elements and located substantially entirely between the adjacent surfaces of 85 said pieces of material and by the movements of which said series of elements are respectively caused to interlock and to separate from each other.

Signed this 21st day of July, 1931. 90
